UNITED STATES PATENT OFFICE.

ROBERT EDWARD SIMPSON, OF BAKERSFIELD, CALIFORNIA.

UNDERREAMER.

No. 892,905.

Specification of Letters Patent.

Patented July 7, 1908.

Application filed January 19, 1906. Serial No. 296,759.

To all whom it may concern:

Be it known that I, ROBERT EDWARD SIMPSON, a citizen of the United States, residing at Bakersfield, in the county of Kern and State of California, have invented a new and useful Underreamer, of which the following is a specification.

This invention relates to that class of underreamers adapted for reaming the hole below a well-casing to allow the casing to descend.

Means are provided for positively expanding the cutters, for positively holding the same in expanded position, and for positively retracting the cutters from expanded position.

It is of the objects of this invention to provide an underreamer which will have no breakable parts liable to come in contact with stones or other solid substances with which the cutters come in contact while doing their work.

I provide a safety pin which acts as a positive expander and a positive reducer for expanding and reducing the size of the underreamer, the same being located in position where it cannot come in contact with boulders, gravel, stones, or other objects which might break or bend the same, and being arranged to prevent the cutters, the cutter-carrying plunger and other parts from falling out in case of accident to the plunger, its support, or its spring; also to secure maximum strength with minimum size of mandrel and other parts; also to provide for maximum collapsing of the tool and certain positive opening or expanding when getting below the bottom of the open end of the well-casing or pipe; also to provide an improved construction in which the cutters work side by side on a perfect hinge and are adapted to collapse completely inside the diameter of the mandrel or body.

The invention comprises the underreamer, the combinations, and the parts hereinafter more particularly described.

I do not limit myself to the exact construction shown and described, but may vary the construction without departing from the spirit of the invention.

The accompanying drawings illustrate the invention.

Figure 1 is a view of the underreamer, looking at the outer face of one of the cutters, the same being in expanded position. Fig. 2 is a fragmental view at right angles to Fig. 1, showing the underreamer in a well casing.

Fig. 3 is a fragmental, longitudinal, axial section on line x^3-x^3 , Figs. 1 and 4, showing the position of parts when the cutters are expanded. Fig. 4 is a view looking up from the bottom of Fig. 3, showing the tool intact. Fig. 5 is a cross section on line indicated by x^5-x^5 , Fig. 3, the cutters being expanded. Fig. 6 is a fragmental detail partly in axial mid-section on line indicated by x^6-x^6 , Figs. 3 and 4. Fig. 7 is an end view of the body of the underreamer. Fig. 8 is a view looking down on one of the cutters detached. Fig. 9 is an elevation of one side of one of the cutters. Fig. 10 is a side elevation of the other side of a cutter. Fig. 11 is an elevation of the inner face of either cutter. Fig. 12 is a fragmental, axial section of the lower end of the underreamer body. Fig. 13 is a cross section on line $x^{13}-x^{13}$, Fig. 3. Figs. 8, 9, 10, 11, and 12, are on a larger scale than the other views.

The invention comprises an underreamer having a forked mandrel or body 1 and expanding cutters 100 movable in the mandrel and having bits 2 and shanks 5, and constructed to form a tie or brace for the forks, prongs or jaws 3 of the mandrel body when the cutters are expanded. Preferably, the cutters are constructed to interlock with the jaws when the cutters are expanded, thereby tying the cutters and jaws tightly together and preventing any looseness, rattling or strain on any part not integral with the mandrel body or with the cutters.

The expanding cutters 100 are duplicates and constructed to be slidingly mounted between the jaws 3, and to embrace the ends of the jaws when the cutters are expanded. To this end the lower ends or tips 4 of the jaws are rounded to spread the cutters apart, and the cutters are provided with shanks 5 constructed to fit between said jaws and are provided with portions to engage, embrace and seat the rounded ends of the jaws to expand the cutters and to tie and brace the jaws; said cutters are provided with slots, grooves, and recesses or pockets to receive, retain, and to be held by other parts of the underreamer, as will be hereinafter more fully set forth.

The shank 5 of each cutter is located wholly on one side of the longitudinal mid-line or axis of the cutter, and the combined thickness of the two shanks is practically equal in width to the space between the jaws of the forked body. Each cutter is provided

on one side of its shank with a recess 6 and on the other side of the shank with two recesses 7, 8, and a rib 9 between them. The outer walls 10, 11, of the recesses 6, 7, are adapted to seat and engage the rounded tips 4 of the jaws to center the cutters and hold them solidly in place on the end of the body when the cutters are expanded.

The jaws are duplicates and each is provided with a flat slanting rib 12, a channel 13 at one side thereof, and a straight rib 14 at the upper end of the channel 13. The shank of each cutter is provided with a rib 15 to enter a seat or pocket 16 forming the upper portion of channel 13 of either jaw, and is also provided with a seat 17 for the mandrel rib 14.

The shank 5 of each cutter 100 is provided with a circular seat 18 and a tapering way 19 for the spring-actuated plunger 20 which is provided with a circular cross-head 21, and upon which the cutters are hinged or pivoted and by which they are normally held in expanded position, as shown in Fig. 3. The upper portion of the circular seat 18 in each shank 5 forms an inwardly-projecting shoulder under which cross-head 21 takes, and thus provides means for pivotally supporting the cutters. Each cutter shank is also provided with a bent slot 22, the lower portion 23 of which extends at right angles to the face 24 of the upper end of the cutter shank, and the upper end 25 of which slot extends toward the edge of the shank on which the cutter is mounted. By reason of the lower portion of the slots 22 extending longitudinally of the shanks of the cutters each cutter shank 5 is guided along pocket 16 and is not changed with respect to its angular position 40 until the rib 15 leaves the pocket 16.

26 is a pin having a head 27, and inserted through one and screwed into the other of the jaws 3. A socket 28 is provided in one of the jaws to seat the head 27 of the pin 45 when the said pin is screwed into the other jaw. Said pin extends through the bent slots 22 of the cutters, and when the cutters are drawn up by the usual spring 29 acting through the plunger 20, the pin 26 will engage the lower ends of the bent slots, while the upper ends of the shanks engage and solidly seat against the lower end of the mandrel.

The wall 30 of the plunger way 19 which 55 is nearest the edge of the shank to which the cutter is attached may be at right angles to the upper face 24 of the shank, while the opposite wall 31 is oblique to said upper face, so that when the cutters are drawn down to 60 bring the pin 26 into the oblique portions 25 of the slots 22 the cutters may swing on the circular head 21 of the plunger to allow the cutters to move toward each other.

By the construction shown, whenever the 65 cutters are drawn down, as shown in Fig. 2,

they will be forced to close toward each other and will be held closed until the cutters are released, whereupon the spring 29 will force the cutters upward and the pin 26, entering the lower portion 23 of the slot 22, will bring 70 the cutters into position to cause the interlocking of the same with the prongs of the mandrel 1.

Each of the cutters is provided with a shoulder 32 to engage the bottom of the well-casing 41 when the underreamer is drawn up to withdraw the same from working position.

34 is a block fastened in the end of the plunger-chamber 35 by dowel pins 36. 80

To assemble the tool, the cutters will be placed with the inside flat faces 37 together and on opposite sides of the plunger and its head to chamber the head 21 and lower the neck of the plunger in the circular sockets 18 and the flaring or tapering ways 19 at the upper end of the shanks; the spring 29 and block 34 and nut 38 being in place, said nut being secured by a cotter-pin 39. Then the bits 2 of the cutters will be spread apart 90 and the safety pin 26 will be brought to the lower end of the slot 22, and the flat faces 24 of the upper ends of the shanks will be brought against the flat face 40 of the lower end of the mandrel body 1 at the upper ends 95 of the jaws. Then the dowel pins 36 will be inserted, and the tool is ready for operation. To insert it in a well-casing 41, the cutters will be forceably retracted to the position shown in Fig. 2, and thereupon the 100 tool may be inserted into the well-casing and lowered until the reamer comes below the shoe 42 of the casing, whereupon the cutters will expand to the position indicated in Fig. 3, and the tool is ready for operation. 105

When it is desired to withdraw the underreamer from the casing, the upward movement of the same will bring the shoulders 32 against the lower edge of the shoe 42; thus, as 110 the mandrel is withdrawn the pin 26 acts on the cutters through the slots 22 to positively retract the cutters from their expanded position until the shoulders 32 are retracted within the mandrel, whereupon or 115 sooner they escape the shoe and pass on up through the casing.

What I claim is:—

1. A forked underreamer mandrel terminating in two jaws, and cutters provided 120 with shanks between said jaws and with portions adapted to embrace and tie together the ends of said jaws when the cutters are expanded.

2. A forked underreamer mandrel terminating in two jaws the ends of which are rounded, cutters provided with shanks between said jaws and with portions to embrace the rounded ends of the jaws to expand the cutters and tie the jaws together. 130

3. An underreamer comprising spring-actuated cutters having reversely-bent slots, a portion of each extending longitudinally of the cutters, a forked mandrel between the 5 forks of which the cutters are mounted, and a pin in the forks extending through the slots and longitudinal seats in the mandrel for the cutters.
4. An underreamer comprising a forked 10 mandrel having jaws that are rounded at the end, cutters slidably mounted between the jaws and provided with reversely-bent slots, a pin in the jaws and bent slots, and means for forcing the cutters to engage the rounded 15 ends of the jaws for expanding the cutters.
5. An underreamer comprising a forked 20 mandrel, provided with jaws, each having a flat slanting rib 12, a channel 13 at one side thereof and a straight rib 14 at the upper end of the channel, and cutters mounted between the jaws of the mandrel and provided with ribs 15 to enter the upper portions of channels 13, and also provided with seats 17 for the mandrel ribs 14.
- 25 6. An underreamer cutter having a shank and a bit that projects laterally from one edge of the shank, and a rib that projects laterally and inwardly from the shank to form a recess to receive a portion of a mandrel.
- 30 7. An underreamer comprising a chambered forked mandrel, a spring-supported plunger in the mandrel provided with a circular cross-head extending between the jaws of the mandrel, and cutters slidably mounted 35 between said jaws and provided with circular sockets for the cross-head and with a channel for the stem of the plunger.
8. An underreamer comprising a forked 40 mandrel, cutters provided with bent slots and arranged between the jaws of the mandrel, a pin in the jaws and slot, and means for moving the cutters lengthwise of the jaws.
- 45 9. An underreamer comprising a forked 45 mandrel, cutters movable in the mandrel
- and each provided with a shank located wholly on one side of the longitudinal mid-line or axis of the cutter, the combined thickness of the two shanks being practically equal in width to the space between the jaws 50 of the mandrel, each cutter being provided on one side of the shank with a recess 6 and on the other side of the shank with the two recesses 7, 8, and a rib 9 between them, the outer walls of the recesses being adapted to 55 seat and engage the tips of the jaws.
10. An underreamer comprising a forked 60 chambered mandrel, the inner faces of the jaws of said mandrel being provided with a channel and a pocket, cutters each provided 65 with a slotted shank one face of which is provided with a rib fitted to the channel and pocket and the other face of which shank is provided with a socket and way for the cross-head and plunger of the cutter-supporting means, the inner sides of said shanks being adapted to move upon each other, a plunger having a cross-head in said socket, and means for guiding the shanks to expand and contract the cutters as they are moved 70 lengthwise between the jaws.
11. An underreamer provided with movable cutters having shanks provided with bent slots, having lower portions extending longitudinally of the cutter shanks and a pin 75 through said slots to expand and contract the cutters as the same move lengthwise of the underreamer.
12. A forked underreamer mandrel having the ends of its forked jaws rounded, and 80 cutters having recesses to seat and engage the rounded ends of the jaws.

In testimony whereof, I have hereunto set my hand at Bakersfield California this 12th day of Jan. 1906.

ROBERT EDWARD SIMPSON.

In presence of—

JOHN GUNDROD,
FRANK GRAY.
